Primary Examiner — Elizabeth J Oswecki(74) Attorney, Agent, or Firm — Banner & Witcoff, Ltd.CLAIM

The ornamental design for a shoe, as shown and described.

DESCRIPTION

FIG. 1 is a front perspective view of a shoe showing my new design;

FIG. 2 is a side view thereof;

FIG. 3 is a rear perspective view thereof;

FIG. 4 is an opposite side view thereof;

FIG. 5 is a front view thereof; and,

FIG. 6 is a top view thereof.

The even-length broken lines within the shaded areas, including the zig-zag shaped broken lines, represent stitching and form no part of the claimed design. The two unshaded eyelets demarcated by uneven-length broken lines within the shaded area form no part of the claimed design. The uneven-length broken lines depicting the remainder of the shoe show features that form no part of the claimed design.
